United States Patent Office

Des. 222,080
Patented Sept. 28, 1971

222,080

DRESSER OR SIMILAR ARTICLE

Raymond T. Carlson, Lookout Mountain, Ga., assignor to Forest Products Corporation, Morristown, Tenn.

Filed Sept. 29, 1969, Ser. No. 19,334

Term of patent 14 years

Int. Cl. D6—01

U.S. Cl. D33—6

FIG. 1

FIG. 1 is a front perspective view of a dresser showing my design.

FIG. 2 is a fragmentary cross-sectional view taken along the section lines 2—2 of FIG. 1.

The side of the dresser not shown is like the side shown while the back is conventional.

I claim:

The ornamental design for a dresser or similar article, substantially as shown and described.
